UNITED STATES PATENT OFFICE

92,311

DESIGN FOR AN AMUSEMENT DEVICE

Earl L. Howe, Dayton, Ohio

Application February 5, 1934, Serial No. 50,625

Term of patent 7 years

To all whom it may concern:

Be it known that I, EARL L. HOWE, a citizen of the United States residing at Dayton, in the county of Montgomery and State of Ohio, have invented a new, original, and ornamental Design for an Amusement Device, of which the following is a specification, reference being had to the accompanying drawing, forming a part thereof,

The figure is a perspective view of an amusement device showing my design.

I claim:

The ornamental design for an amusement device, as shown.

Signed at Dayton, Ohio, this 15th day of December, 1933.

EARL L. HOWE.
